Primary Examiner — Elizabeth Albert*(74) Attorney, Agent, or Firm* — Massina Pat. & TM Law PLLC(57) **CLAIM**

The ornamental design for a storage container, as shown and described.

DESCRIPTION

FIG. 1 is an isometric view of a storage container according to the present invention.

FIG. 2 is a front elevation view of FIG. 1.

FIG. 3 is a rear elevation view of FIG. 1.

FIG. 4 is a left side view of FIG. 1.

FIG. 5 is a right side view of FIG. 1.

FIG. 6 is a top plan view of FIG. 1; and,

FIG. 7 is a bottom plan view of FIG. 1.
